STENCIL FOR THE PRODUCTION OF COMPOSITE ORNAMENTATIONS ON EMBROIDERY MACHINES

Application filed March 29, 1928. Serial No. 265,564.

This invention relates to improvements in the art of decorating fabrics, and has particular reference to a stencil for producing a composite color and embroidery ornamentation on fabrics.

In the production of this type of fabric, it has been customary to perform the coloring and embroidery operations successively and one of the principal problems encountered has been to secure accurate registration of the color pattern with the bas-relief embroidery ornamentation so that the latter, which is preferably applied to the fabric subsequent to the coloring thereof, will not overlap any portion of the color pattern.

One method heretofore employed for producing this composite ornamentation makes use of a pantograph embroidering machine for forming a stencil which is subsequently utilized to paint the color pattern on the fabric. Briefly, in this method a blank stencil is temporarily affixed to the fabric and the ornamentation is delineated thereon, after which the stencil is removed, the delineated design cut out, and the stencil then relocated at its original position on the fabric so that the latter can be colored by means thereof.

Another known method consists in forming, by stitching on the fabric, an outline of the design to be embroidered, making a tracing of the outline, producing from said tracing a stencil of the areas to be color-filled, painting said areas by the use of the stencil, and finally embroidering the outline originally produced.

It is known that with the methods just referred to, accurate registration of the two ornamentations has been very difficult of attainment and the embroidery has often overlapped the color design. This is primarily due to the complicated manner in which the stencils are made and the inability to always relocate the stencils in proper position on the fabric prior to the coloring operations.

An object of the present invention is to overcome the difficulties encountered in the use of known methods by materially simplifying the making of the stencil and in supporting the same in position with respect

to the fabric in such manner that the color pattern produced thereby will be accurately located on the fabric so as to properly register with the embroidered ornamentation.

Another object is to provide a stencil adapted for the application to a fabric of a color pattern constituting a part of a composite ornamentation and to form in said stencil a recess or recesses for receiving one or more needles of an embroidery machine, with one of said recesses disposed below the ornamentation on the stencil in vertical alignment with a predetermined point thereon which coincides with a similar point on the fabric to be decorated.

Another object is to so construct the stencil that the needles of an embroidery machine may be utilized in properly locating the stencil relative to the fabric to be colored, and the presser member of said machine employed to retain the stencil in position during the coloring operation.

Another object is to support and reinforce the stencil so that it will lie flatly and rigidly against the fabric while the color is being applied thereto.

The above and other objects will appear more clearly from the following detailed description, when taken in connection with the accompanying drawing, which illustrates a preferred embodiment of the inventive idea.

In the drawing—

Figure 1 is a fragmentary diagrammatic view in vertical section of an embroidery machine which may be used in carrying out the present invention;

Figure 2 is a fragmentary plan view of the completed fabric with the stencil indicated in broken lines in the position thereon which it would be made to assume when applying the color pattern;

Figure 3 is a plan view of the stencil; and

Figure 4 is a fragmentary vertical section on the line 4—4 of Figure 3 with the presser member and associated parts of an embroidery machine in position to hold the stencil in place.

In Figure 1 there is illustrated a portion of an embroidery machine of a well known construction in which the vertical emboid-

ery frame 5 is movable relative to the needle bar 6 in vertical, horizontal and diagonal directions under the control of an automatic jacquard mechanism (not shown), whereby each of the various needles of the machine, one of which is shown at 7, is operated by the horizontal reciprocation of the needle bar relative to the shuttle bar 8 to form an embroidered design in the fabric 9 supported in the frame 5 on the rollers 10^a and 11. As is well known in machines of this type, the various movements of the frame 5, and consequently of the fabric 9, relative to the needles 7, are controlled by a mechanism which is set in accordance with the particular design being made. It is to be understood that in so far as the present invention is concerned, this automatic control mechanism may be of the jacquard type or any other form of mechanism, such as the pantograph.

In the production of composite ornamentations, such as embroidery and color patterns, it is proposed by the present invention to employ a stencil 10 for the application of the color design to the fabric by supporting said stencil upon the needles 7 in fixed relation to the fabric and lying snugly against the same during the application of the color thereto. In order to accomplish this, it is quite desirable, though not absolutely necessary, that the color work be done before the embroidery, since the latter is a bas-relief ornamentation and if made first might prevent the stencil from engaging the fabric in the proper manner. Furthermore, it is proposed to utilize the presser member 11^a of the machine to aid in retaining the stencil in proper position against the fabric. This presser member, as is well known, comprises a number of fingers or arms 12, which, in the ordinary operation of the machine, engage the fabric in proximity to the needles 7 so as to hold the fabric against excessive outward movement when the needles 7 are withdrawn after making a stitch. In placing the stencil in position, the presser member is first moved outwardly a slight distance equal to the thickness of the stencil and then the lower edge of the latter is inserted between the fingers 12 and the fabric, with said lower edge resting upon a needle or needles 7. The presser fingers will then engage and assist in supporting the stencil in a vertical position against the fabric.

In preparing the stencil, the composite design which is later to be applied to the fabric is first sketched upon a sheet of paper usually employed for this purpose. The design so sketched is a complete motif or repeat and it is now necessary to determine a point relative to the embroidery part of the ornamentation which may be made to coincide with a point on the fabric at which the needle which is to stitch the pattern will commence its operation after the color design has been ap-

plied. For convenience, the point on the sketch paper may be located in a vertical line which is coincident with the mean distance between parallel vertical lines marking the horizontal extremities of the embroidery portion of the design. This mean vertical line is drawn on the sketch and at a predetermined distance below the lowest extremity of the composite design a horizontal line is drawn which will intersect said mean vertical line. The distance of the horizontal line from the pattern may be four inches, for instance, and represents the amount of upward vertical movement which it is necessary to impart to the fabric prior to the coloring operation and said horizontal line determines the lower edge of the stencil which is made from the sketch.

It now becomes necessary to transfer the design on the sketch to a blank stencil. To do this, the stencil sheet may be provided with a vertical line such as the line 12' placed in a position which is determined by the nature of the design to be transferred thereto and the tracing paper upon which said sketch is made is then reversed and laid upon the blank stencil with the mean vertical line on said sketch coinciding with the vertical line which has been made upon the blank stencil and the horizontal line on said sketch registering with the bottom edge of the stencil blank. By rubbing upon the reverse or uppermost side of the sketch paper, the design, which has been made thereon with soft pencil or crayon, may be transferred to the stencil blank and at the same time the point of intersection of the mean vertical line and the horizontal line on the sketch will also be indicated on the lower edge of said blank. A recess or notch 13 is now formed at said point on the lower edge of the stencil to receive the needle 7 which is to make the embroidery portion of the motif represented by said stencil when the latter is placed in the position shown in Figure 1. In order to further assist in maintaining the stencil in proper operative position, the lower edge thereof may also be formed with one or more recesses 14 similar to the recess 13, and each of the recesses 14 is spaced from the recess 13 a distance equal to that between the needle 7 engaged in the latter recess and the next adjacent needles so that said recess or recesses 14 will receive the next adjacent needle or needles on the needle bar.

It is conceivable that instead of making the stencil as above described, the stencil sheet may be obtained in its completed form, that is with the pattern already cut out. A point on the lower edge of the stencil may then be determined as described in connection with the sketch and the needle recess formed at said point, after which other recesses are made in the same manner as heretofore set forth.

It is preferable that the lower edge of the stencil be reinforced so that repeated mountings of the stencil upon the needles will not wear away the material of the stencil forming the edges of said recesses, thereby avoiding the possibility, after repeated use, of the color pattern being inaccurately applied to the fabric. For this purpose, a metallic strip 15 is applied to the lower edge of the stencil and formed with notches or recesses therein coinciding with the recesses 13 and 14. The stencil is further preferably provided with a supporting frame consisting of horizontal and vertical strips 16 and 17 to which the stencil is secured, said strips being arranged inwardly of the marginal edges of the stencil, with the ends of the vertical strips 17, and particularly the lower ends thereof, extending practically to the upper and lower edges of the stencil. With the stencil attached to this frame the same will have sufficient rigidity imparted thereto to prevent it from bending when being applied and held in proper position on the fabric. The extension of the lower ends of the vertical strips 17 to overlapping position relative to the metallic strip 15 will avoid any bending of the lower portion of the stencil when said metallic strip is inserted into the space between the fabric 30 and the fingers 12.

After the stencil has been made as above described, the fabric is placed upon the rollers 10^a and 11 and the automatic control mechanism of the embroidery machine is prepared or set in accordance with the embroidery design so as to control the movements of the frame 5 in predetermined directions during the course of the embroidery operation. The fabric is adjusted relative to the 40 needle bar so that a predetermined point on the fabric which corresponds to the starting point of the embroidery operation is horizontally aligned with the particular needle that is to perform the stitching of one motif. The fabric is now moved upwardly under the influence of the previously-mentioned control mechanism a distance equal to the space between the lower edge of the stencil and the lower extremity of the composite ornamentation, which space, for example, has hereinbefore been given as four inches. During this movement, the frame 5 and fabric may, in accordance with the setting of the control mechanism, be moved in any one or all of 50 the directions of which the frame is capable so that it is possible that when the frame reaches its final position, the starting point on the fabric for the embroidery pattern will be vertically offset relative to the original position of said point. The movement of the fabric above described brings it into proper position to have the color portion of the ornamentation applied and the stencil is now placed in position as previously described. 60 After application of the color, the fabric is

removed in a reverse direction from that originally imparted thereto to again bring the predetermined starting point of the embroidery work into alignment with the needle 7 which is to perform said work. The stencil 70 is removed and the machine started to accomplish the regular embroidery operation and, in so doing, the pattern produced by the latter operation will exactly register with the color pattern previously applied to the fabric. 75

What is claimed is:

1. A stencil for use with embroidery machines, including a stencil sheet having an ornamental pattern for fabrics thereon and having a recess formed therein adjacent to the bottom edge thereof for receiving a needle of the machine to support said stencil in position relative to a fabric to be colored to orient said stencil with respect to said fabric. 80

2. A stencil for use with embroidery machines, including a stencil sheet having an ornamental pattern for fabrics thereon and having a recess formed therein adjacent to the bottom edge thereof for receiving a needle of the machine to support said stencil in position relative to a fabric to be colored to orient said stencil with respect to said fabric, and a supporting frame to which the stencil sheet is attached. 90

3. A stencil for use with embroidery machines, including a stencil sheet having an ornamental pattern for fabrics thereon and having a recess formed therein adjacent to the bottom edge thereof for receiving a needle of the machine to support said stencil in position relative to a fabric to be colored to orient said stencil with respect to said fabric, and a supporting frame for said stencil sheet including strips secured to said sheet at points inwardly of the edges thereof. 95

4. A stencil for use with embroidery machines, including a stencil sheet having an ornamental pattern for fabrics thereon and having a recess formed at the lower edge of said sheet for receiving a needle of the machine to support the stencil in position relative to the fabric to be colored to orient said stencil with respect to said fabric, and a supporting frame for said sheet including strips secured thereto inwardly of its edges, certain of said strips extending to the edge of the sheet having said recess therein. 100

5. A stencil for use with embroidery machines, including a stencil sheet having an ornamental pattern for fabrics thereon, and a reinforcing strip along the lower edge of said sheet and having a recess formed therein for receiving a needle of the machine whereby the stencil is supported in position relative to the fabric to be colored to orient said stencil with respect to said fabric. 115

6. A stencil for use with embroidery machines, including a stencil sheet having an ornamental pattern for fabrics thereon, a reinforcing strip along the lower edge of said 120

sheet and having a recess formed therein for receiving a needle of the machine whereby the stencil is supported in position relative to the fabric to be colored to orient said stencil with respect to said fabric, and a supporting frame for said sheet including strips secured thereto inwardly of its edges, certain of said strips extending to said reinforcing strip.

10 In testimony whereof I have affixed my signature.
